Primary Examiner — Sandra Snapp(74) *Attorney, Agent, or Firm* — Donald J. Ranft; Collen IP**CLAIM**

The ornamental design for a dial, as shown and described.

DESCRIPTION

FIG. 1 is a front right perspective view of a dial showing my new design;

FIG. 2 is a rear left perspective view thereof;

FIG. 3 is a front view thereof;

FIG. 4 is a rear view thereof;

FIG. 5 is a right side view thereof;

FIG. 6 is a left side view thereof;

FIG. 7 is a bottom view thereof; and,

FIG. 8 is a top view thereof.

The portions of the dial shown in broken lines depict environmental subject matter only and form no part of the claimed design.

1 Claim, 3 Drawing Sheets(56)
